UNITED STATES PATENT OFFICE.

EDWARD L. HARRINGTON, OF ERIE, PENNSYLVANIA, ASSIGNOR TO G. H. WILLIAMS COMPANY, OF ERIE, PENNSYLVANIA, A CORPORATION OF PENNSYLVANIA.

CLAM-SHELL BUCKET.

Application filed September 25, 1924. Serial No. 739,940.

The invention is designed to improve the construction of clam shells, particularly the head carrying the closing sheaves and from which the corner bars extend. Such heads have been cast and sometimes fabricated but there are disadvantages in the different constructions. In the present invention I fabricate this head of ordinary metal plates and rigidly secure these plates together by clamping bolts, the plates being separated by distance sleeves on the bolts. I carry the clamping action through the different pins on which the sheaves are mounted by supplying such pins with distance sleeves and clamp the same. Further I bend the corner irons which are made rigid with the head so as to bring a portion of said irons parallel with the plates forming the head, thus providing a rigid and durable head and at the same time one that may be very cheaply constructed. Features of the invention will appear from the specification and claims.

The invention is illustrated in the accompanying drawings as follows:

Fig. 1 shows a side elevation of the clam shell.

Fig. 2 a detail view of the clamping means.

Fig. 3 an end elevation.

Fig. 4 an enlarged section on the line 4—4 in Fig. 6.

Fig. 5 a section on the line 5—5 in Fig. 6.

Fig. 6 a side elevation of the head.

Fig. 7 an end elevation of the head.

1 marks one scoop member, 2 the other scoop member, 3 and 4 the pivot arms on the scoop members, 5 the hinge pin of the scoop members, 6 an opening lever locked with the arms 3, 7 a closing sheave on the opening lever, 8 a pin on which the sheave is mounted, 9 a second sheave on the lever, and 10 a pin on which the sheave 9 is mounted. The head is made up of two metal side plates 11 having depending brackets 12 at each side

45 of the side bars, these brackets being simply formed to extend the plate 11 and secured thereto by riveting or any convenient means. Pins 14 extend through corner bars 15 and the plates 11. The corner bars are secured

50 to the scoop member 1 by pins 16 and to the bracket plate 12 by securing means 17. Several of these clamping means are used in the structure and involve a bolt 18 extending through the side plates or bracket and a distance sleeve 19 between such plates. A

washer 13 is arranged between the ends of the bars 15 and the plates 11 corresponding in thickness to the plate 12. A distance piece 20 in the form of a cable guide is arranged on the pin 14 between the plates 11. Corner 60 bars 21 are arranged on the pins at the outside of the bars 15. Distance sleeves 22 are arranged on the pins 14 and extend through the bars 21 forming a clamping means between the head 23 of the pin 14 and a nut 24. It will readily be seen that by drawing up the nut the whole system may be clamped, the bars 21 being journaled on the sleeves 22. Washers 25 may be arranged between the bars 21 and the bars 15.

The plates 11 are clamped together by a clamping means 27 and 28, these clamping means corresponding to those shown in Fig. 2.

A sheave 29 is journaled on the distance 75 sleeve 30 between the plates 11 and the plates are clamped together on this sleeve by the bolt or pin 31. A sheave 32 is journaled on the distance sleeve 33 and the plates clamped together on this sleeve by the bolt 33^a.

A lifting cable 34 is secured to a clamping means 35, the distance piece in the clamping means being in the form of a spool similar to the spool 37 shown in Fig. 5. The closing cable extends around the guide 85 sheave 32, the closing sheave 9 on the closing lever, the sheave 29, sheave 7 and is secured to the spool 37 arranged on a pin 36 between the brackets 12.

The operation of the clam shell will be readily understood in that it operates in a manner common to clam shells now in use. It will be noted that by this construction a very rigid and durable head is fabricated in a very cheap and efficient manner and that the corner bars which are rigid with the head are secured thereto and tend to brace the head by having a portion of the bars parallel with the plates forming the head.

It will be noted that where the distance sleeve, as 30, or 33, is arranged around the pin it protects the pin from wear and all that is necessary to renew with excessive wear is the distance piece. It will be understood further that in many places these 105 sheaves where they operate under rather severe conditions must be made or bushed of material standing such use as manganese steel. Under these conditions the pins may be made of ordinary material and it is only 110

necessary to make the distance piece of such material.

What I claim as new is:—

1. In a clam shell bucket, the combination of connected scoop members; a head formed of side plates of uniform thickness and rigidly secured together; two corner bars rigidly secured to the head; a pin extending through said corner bars; a distance sleeve 15 on the pin between the side plates of the head; corner bars pivotally mounted on the pin outside of the first-mentioned corner bars and extending to the other scoop member; and clamping means on the pin extending through the pivotally mounted corner bars.
2. In a clam shell bucket, the combination

of connected scoop members; a head comprising parallel plates of uniform thickness; a closing sheave arranged between the side 20 plates; a distance sleeve on which the sheave is journaled; a clamping pin extending through the plates and sleeve; corner bars rigidly secured to the head; a pin extending through said corner bars and side plates; 25 a distance piece on said last-mentioned pin between the side plates; a second set of corner bars pivoted on said last-mentioned pin; and means for clamping the side plates on said last-mentioned distance piece 30 through said last-mentioned pin.

In testimony whereof I have hereunto set my hand.

EDWARD L. HARRINGTON.
